R. L. WILCOX.
METHOD AND DIE FOR TRIMMING BLANKS.
APPLICATION FILED FEB. 26, 1918.

1,294,987.

Patented Feb. 18, 1919.

INVENTOR -

RICHARD LESTER WILCOX,

by *George E. Hall* Atty.

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

METHOD AND DIE FOR TRIMMING BLANKS.

1,294,987.

Specification of Letters Patent. Patented Feb. 18, 1919.

Application filed February 26, 1918. Serial No. 219,171.

To all whom it may concern:

Be it known that I, RICHARD LESTER WILCOX, a citizen of the United States, and a resident of Waterbury, county of New Haven, State of Connecticut, have invented certain new and useful Improvements in Methods and Dies for Trimming Blanks, of which the following is a specification.

My invention relates more especially to methods and dies by which a blank can be given a polygonal cross section such as the square, hexagon or octagon shapes of bolt heads, nuts and the like or a many-sided shape of any kind, such for instance, as a circular section with flat sides, as is formed on shackle bolts and the like. It will be understood that by "polygonal" I mean any such shape. A blank may also be cut so as to have a circular section, and when I refer hereinafter to a "trimmed" section, it will be understood that I mean a section of any shape which has been cut or trimmed by the dies, either entirely around it or on any particular portion.

One of the objects of my invention, among others, is to give a trimmed cross section to a blank without tearing the metal so that the finished product will have its faces smooth and of a uniform level throughout.

As the trimming of bolt heads and nuts has heretofore usually been carried out, the blank has been passed through a die having a suitably shaped opening therein, in such a way that the cutting edges of the die enter the blank by cutting for a short distance and then, the resistance to the cutting pressure having been sufficiently decreased, the remaining metal is practically torn from the blank, leaving the faces of the blank rough and in most cases, with depressions below what should be the level of the face. For some classes of work, the bolts or nuts thus formed are undesirable because of their unsightly and unfinished appearance.

I have found that trimmed blanks with a very superior finish on the faces may be produced if the metal of the blank as it is being cut away is not permitted to spread out, but is controlled so that the cutting pressure will be maintained substantially constant throughout the operation.

This general method may be carried out in different ways and I have found that the

specific way which I am about to describe gives very satisfactory results.

55

The annexed drawings illustrate several of the many forms of dies with which my novel method may be carried out.

In the drawings, Figure 1 represents a form of die, together with a support therefor, and a means whereby a blank may be forced into the die;

Figs. 2, 3 and 4 represent, on an enlarged scale, the action of the die as the blank passes through, Figs. 2 and 3 being sections 65 on line 2—2 of Fig. 5 and Fig. 4 being a section on line 4—4 of Fig. 5;

Fig. 5 represents a portion of the front view of the die illustrated in Figs. 1, 2, 3 and 4; and

Fig. 6 represents a modification of the die in section.

The corresponding parts are referred to both in the drawings and in the specification by similar reference characters.

75

In the drawings 10 represents an illustrative form of die which, in this instance, is of the solid type having a cylindrical recess 11 extending for a short distance below its face and an opening 12, having a polygonal section (in this instance a hexagon) in alignment with the cylindrical opening 11. Preferably the polygonal opening has a maximum diameter slightly less than that of the cylindrical opening 11 and also preferably the bottom of the cylindrical opening 11 is slightly coned so as to produce the curved cutting edges 15 shown in Figs. 1 to 4, inclusive. Preferably the opening 11 will be shaped so as to give a proper clearance to 90 the cutting edges 15.

85

Preferably the opening 11 is made slightly smaller in diameter than the diameter of the head 13 of the blank which, in this instance, is represented as a bolt on which a hexagon head is to be formed.

95

By any suitable means, such as a plunger 14, the head 13 is first forced into the circular opening 11. The beginning of this operation is shown in Fig. 2. The sharp outer 100 edges of the die 10 around the circular opening 11 will reduce the diameter of the head 13 somewhat, as is shown in Fig. 3. The continued travel of the plunger will carry the head 13 past the cutting edges 15 of the 105 polygonal opening 12. These cutting edges

remove portions of the metal of the head 13, and as will be obvious by an inspection of Fig. 4, this cut-away metal is controlled in the cylindrical opening 11 and is not permitted to diverge from the cutting edges 15, as would be the case if the cutting edges 15 were at the surface of the die 10.

The blank is pushed into the polygonal opening 12 a sufficient distance so that the bottom of the head will pass the cutting edges 15, and the polygonal head is thus completely formed.

If desired, the blank can be pushed all the way through the die and dropped out at the rear, but preferably I stop the motion of the blank toward the left of Fig. 4 before the blank has passed out of the polygonal opening 12, and then I return the blank toward the right of Fig. 4. This causes the bottom 20 of the head to engage the chip 16 sufficiently to eject the chip and clear the die for the next operation. A plunger 17 is suitable for giving this backward motion to the blank.

25 Approximately the same results may be obtained in the form of die shown in Fig. 6, in which a conical opening 18 is used instead of the cylindrical opening 11, the remainder of the die being the same as 10. 30 Then the chip is restrained and controlled in the conical opening although not to the same extent as when the form of die 10 is used.

While I have illustrated the formation of a hexagonal head on a bolt blank, it will be understood that a polygonal form can be given to any blank by my novel method and the dies which I have illustrated.

It will also be understood that if circular blanks are to be produced, then the opening 40 12 will be circular and of the diameter of the finished blank. The chip will be controlled by the opening 11 in the same manner as when a polygonal cross section is produced.

While I have shown in Fig. 1, parts which 45 obviously can be connected to a machine so as to carry out my novel method automatically, it will be understood that the same results may be obtained by forcing the blank in any manner through dies embodying the 50 novel structure which I have disclosed.

It will also be obvious that the same results are obtained if the die is forced over the blank instead of forcing the blank into the die. When I refer to the forcing of the 55 blank into the die, I mean the relative motion of the blank and the die, whether one or the other or both are moving.

While I have found it preferable to make the opening 11 cylindrical and somewhat 60 smaller than the blank, this is not essential. The opening may be of any desired shape and size, so long as it is small enough to prevent the chip spreading to permit the die breaking off the uncut material before the 65 cut is completed. By making the opening

smaller than the blank and not substantially larger than the opening 12, the metal of the chip is held closely to the blank so as to prevent the sudden breaking through of the die and the consequent tearing of the surfaces.

70 It will be understood that preferably the polygonal openings 12 and 19 are made slightly pyramidal so as to relieve the cutting edges at the top of the openings.

It will also be understood that the cutting edges 15 may be formed on separate cutter bars held in the die and my invention is not limited to the solid type of die which I have chosen for illustrative purposes.

75 I claim:

1. The method of giving a trimmed cross section to a blank, consisting of cutting from one end of the blank to the other and preventing the spreading of the chips while the 85 cutting is taking place to prevent the tearing of the material of the blank as the cutting progresses.

2. The method of giving a trimmed cross section to a blank, consisting of cutting from 90 one end of the blank to the other and compelling all of the removed material to flow in a direction substantially parallel with the direction of the cut.

3. The method of giving a trimmed cross 95 section to a blank, consisting of forcing a blank into a recess of smaller area of cross section than the area of a cross section of the blank and of approximately the same contour and then into an opening adjacent the 100 recess, to cause the material removed by the passage through the opening to remain in the recess.

4. The method of giving a trimmed cross section to a blank, consisting of forcing a 105 blank into a recess, and then into an opening adjacent the recess, to cause the material removed by the passage through the opening to remain in the recess.

5. The method of giving a trimmed cross 110 section to a blank, consisting of forcing a blank into a recess and then into a polygonal opening adjacent the recess, to cause the material removed by the passage through the polygonal opening to remain in the recess, and then returning the blank through 115 the opening and the recess, whereby the removed material is pushed out of the recess.

6. The method of giving a trimmed cross section to a blank, consisting of forcing a 120 blank into a recess of slightly smaller diameter than the blank and of approximately the same contour and then into an adjacent opening whose maximum diameter is not greater than that of the recess.

7. The method of giving a trimmed cross section to a blank, consisting of forcing a blank into a recess of slightly smaller diameter than the blank, and then into an opening whose maximum diameter is not greater 125 130

than that of the recess and then returning the blank through the opening and the recess, whereby the removed material is pushed out of the recess.

5 8. A die having an opening with cutting edges at one end of the opening and a recess adjacent the cutting edges and in alinement with the opening, the boundaries of the recess lying outside the boundaries of the

10 opening.

9. A die having an opening with cutting edges at one end of the opening and a cylindrical recess adjacent the cutting edges and in alinement with the opening and having a

15 diameter not less than the maximum diameter of the opening.

10. A die having an opening with cutting edges at one end of the opening in combination with a recess adjacent the cutting edges

20 and in alinement with the opening and

means whereby a blank may be forced through the recess and into the opening.

11. A die having an opening with cutting edges at one end of the opening and a recess adjacent the cutting edges and in alinement 25 with the opening, means whereby a blank may be forced through the recess and into the opening and means whereby the finished blank may be moved backwardly out of the die.

12. A die having an opening with cutting edges at one end of the opening and a recess adjacent the cutting edges and in alinement with the opening, the area of the recess exceeding the area of the opening by an 30 amount great enough to receive the chips from the cutting edges and small enough to prevent the chips spreading radially away from the blank.

RICHARD LESTER WILCOX.
